UNITED STATES PATENT OFFICE.

ANNA A. GILLETT AND GARLAND L. GILLETT, OF MILWAUKEE, WISCONSIN.

GARMENT-SUPPORTER.

SPECIFICATION forming part of Letters Patent No. 448,228, dated March 17, 1891.

Application filed June 16, 1890. Serial No. 355,530. (No model.)

To all whom it may concern:

Be it known that we, ANNA A. GILLETT and GARLAND L. GILLETT, of Milwaukee, in the county of Milwaukee and State of Wisconsin, have invented certain new and useful Improvements in Garment-Supporters; and we do hereby declare that the following is a full, clear, and exact description of the invention, which will enable others skilled in the art to 10 which it pertains to make and use the same, reference being had to the accompanying drawings, and to the letters of reference marked thereon, which form a part of this specification.

15 The main objects of our invention are greater convenience and economy in the manufacture, commercial handling, and use of this class of articles, ease and convenience in application and adjustment, and to relieve 20 the hips and lower limbs of the support of clothing, thereby allowing freedom of movement and promoting health and comfort.

It consists of certain novel features in the construction and arrangement of the parts, 25 hereinafter described, and pointed out in the claims.

In the accompanying drawings like letters designate the same parts in the several figures.

Figure 1 is a perspective view of our improved device. Fig. 2 is a view, on an enlarged scale, of the reverse side of the suspender-buckle, a portion of one of the hip-pieces, and of the branching suspender-ends, showing the method of attaching the same to 30 the buckle; and Fig. 3 is a similar view on an enlarged scale, showing the method of attaching the hip-pieces and the rear suspender-ends to the shoulder-bands of the suspenders.

35 A A represent the shoulder-bands of a pair of ordinary suspenders, joined or crossed in the usual way at the back and provided in the rear with branching ends B B and in front with branching ends or straps C C, which are adjustably attached to the shoulder-bands A A by buckles c c, in the usual manner.

40 D D are hip-pieces, preferably formed of a single piece of round cord and stitched to the shoulder-straps A A at the back with the loop or strap a, by which the ends of said shoulder-bands are joined, and the branching ends B B are attached thereto, as shown in Fig. 3. At

its ends this cord forming the hip-pieces is preferably provided with rings d d, as shown in Figs. 1 and 2, by which they are fastened upon the hooks of the suspender-buckles c c, 55 and adjusted, together with the front suspender-ends C C, upon the shoulder-bands A A. These hip-pieces are so formed and attached to the suspenders as to hang at each side over the hips of the wearer and draw directly through the shoulder-straps A A of the 60 suspenders over the shoulders.

E E are side bands or sections, preferably composed partly of inelastic portions e e and partly of elastic portions e' e', the latter being attached to the former by means of buckles e² e² or other suitable means, by which the said side bands may be adjusted in length to suit persons of different sizes and stockings of different lengths. Branching terminal 70 straps F F, provided with suitable fastenings f f for attachment to the tops of the stockings, are secured to the lower ends of the side bands or sections E E. At their upper ends the side bands or sections E E are attached to the hip-pieces D D by means of self-adjusting sliding fastenings G G, which may be conveniently formed of wire coiled to form sleeves, through which the cord constituting the hip-pieces loosely passes, and loops for the attachment 80 of the side bands or sections E E. By this means of attaching the side sections E E to the hip-pieces D D they are kept in proper position over the thighs, the weight or pull of the stockings is equally distributed through 85 both branches of the hip-pieces to the front and back of the shoulder-bands of the suspenders, and the latter are prevented from being pulled off from the shoulders. The supporters and suspenders are also relieved 90 of excessive or unequal strain when the body or limbs of the wearer assume various positions.

By forming the hip-pieces D D of a single cord or piece of material a single fastening 95 suffices to secure both to the back of the suspenders, and greater security is attained than would be if the hip-pieces were made and attached separately.

Great convenience and economy in the 100 manufacture, in the commercial handling, and in the individual use of the article arise

from combining the hose-supporters with the suspenders, both of which are provided with suitable means of adjustment to adapt them to persons of different sizes and to stockings and clothing of various lengths.

By connecting the hip-pieces at their front ends with the front fastenings or ends of the suspenders they are adjusted when the shoulder-bands are taken up or let out.

10. The hip-pieces D D may be made of tape or bands and attached permanently at the front ends to the shoulder-bands A A of the suspenders above the buckles *c. c.* In short, various changes in the details of construction 15 of the article may be made without departing from the spirit of our invention.

Although specially designed for boys' use, our combined suspenders and hose-supporters may be conveniently worn by adults with bi-

20. cycle suits or other costumes embracing knee-breeches and long hose.

We claim—

1. In a garment-supporter, the depending 25 hip-pieces adjustably connected with the suspenders at the front and provided with side pieces having at their lower ends hose-attach-

ing devices, substantially as and for the purposes set forth.

2. In a garment-supporter, the depending 30 hip-pieces adapted to be connected to the suspenders and provided with side pieces having at their lower ends hose-attaching devices and at their upper ends a sliding connection with the hip-pieces, substantially as and for the purposes set forth.

3. Garment-supporters consisting of depending 35 hip-pieces connected with the suspenders in front and behind, their connections therewith in front being adjustable, and side pieces having self-adjusting sliding connections at their upper ends with said hip-pieces and provided at their lower ends with suitable fastenings for attachment to the hose, substantially as and for the purposes set forth.

In testimony that we claim the foregoing as 40 our own we affix our signatures in presence of two witnesses.

ANNA A. GILLETT.
GARLAND L. GILLETT.
